ABSTRACT OF THE DISCLOSURE

A hydrocarbon conversion process involving alkylation and disproportionation of low octane C_7 alkane streams in the presence of isobutane to form higher octane mixtures of predominantly saturated hydrocarbons, said process utilizing a mixture of fluorosulfonic acid and antimony pentafluoride as a catalyst.

SUMMARY OF THE INVENTION

This invention relates to a novel process for producing a high octane hydrocarbon mixture from a low octane C_7 hydrocarbon stream and, more specifically, to an alkylation-disproportionation process for octane upgrading of a heptane stream using a system comprised of a low octane heptane feed, an isobutane feed and a catalyst which is a mixture of fluorosulfonic acid and antimony pentafluoride.

In accordance with the instant invention, a low octane heptane feed (low octane heptane being used here in the sense of any feed which is composed predominantly of one or more low octane C_7 saturated hydrocarbons such as n-heptane or the methyl hexanes) is disproportionated and alkylated in the presence of a branched saturated hydrocarbon, isobutane, by a mixture of fluorosulfonic acid and antimony pentafluoride to yield a product stream which is predominantly a mixture of high octane alkanes. This process may be carried out at about atmospheric pressure and below ambient temperatures.

BACKGROUND OF THE INVENTION

One of the major problems in petroleum refining is the production of low octane hydrocarbon streams during the refining process. These low octane streams must then be converted to mixtures of hydrocarbons having a higher octane number. Various techniques have been developed for this purpose including alkylation, isomerization, disproportionation and various combinations of these individual techniques. Various catalysts have been used for the accomplishment of alkylation, isomerization and disproportionation among which are Friedel-Crafts type of catalyst including hydrogen fluoride-boron trifluoride mixtures and the so-called "super acids" such as fluorosulfonic acid-antimony pentafluoride mixtures. However, no good processes for handling C_7 streams have been developed. The instant invention is directed to an improved alkylation-disproportionation procedure by which higher octane mixtures of hydrocarbons can be formed from C_7 streams than has been heretofore accomplished. Using the instant invention, for example, a normal heptane feed treated with a fluorosulfonic acid-antimony pentafluoride mixture in the presence of isobutane is disproportionated and alkylated and the pentanes, hexanes and heptanes formed are substantially at their isomeric equilibria in which isopentane, dimethylbutanes and, for the heptanes, dimethylpentanes and triptane predominate.

BRIEF DESCRIPTION OF THE DRAWINGS

The Figure shows a flow diagram for one mode of carrying out the instant invention.

2**STATEMENT OF THE INVENTION**

An embodiment of the instant invention is illustrated in the flow diagram of the Figure. A C_7 cut of light naphtha, preferably after drying, dearomatization and desulfurization to reduce catalyst poisoning, is mixed with isobutane and introduced through line 1 into stirred reactor 2. The isobutane to C_7 feed weight ratio is maintained between about 0.1 to about 5, more preferably, between about 0.5 to about 2 and, most preferably, between about 0.8 to about 1.2.

In reactor 2 the feed is stirred with liquid catalyst entering through line 3. Make-up catalyst enters through line 4 and consists of a mixture of 0.1 to about 2.0 volumes, more preferably, about 0.2 to about 1.2 and, most preferably, about 0.5 to about 1.0 volumes of antimony pentafluoride per volume of fluorosulfonic acid. Preferably, as high a purity of fluorosulfonic acid and antimony pentafluoride as is economically feasible is used, and special precautions should be used to keep these catalyst components as dry as possible prior to and during use.

The temperature in reactor 2 is kept between about -20° F. and about 70° F., more preferably, between about 0° F. and about 40° F. and, most preferably, between about 10° F. and about 30° F. Advantageously, the entire process of the instant invention is run at or near atmospheric pressure.

Space velocities are important for achieving maximum octane upgrading and depend upon reactor temperature and a lower space velocity will naturally be used at a lower reaction temperature. It has been found that at about 70° F. space velocities between about 0.5 to about 3.0 volumes of feed per volume of catalyst per hour into the reactor are useful. At about -20° F. a space velocity between about 0.01 to about 0.05 volumes of feed per volume of catalyst per hour is used and, at about 14° F. a space velocity between about 0.10 to about 0.15 volumes of feed per volume of catalyst per hour is employed. Catalyst is used throughout to mean a mixture of fluorosulfonic acid and antimony pentafluoride.

The reactor effluent is passed into settler 5 where the catalyst phase separates as a bottom layer and is recycled to reactor 2 through line 6. A slip stream of catalyst is taken off via line 7 for catalyst rejuvenation. In the catalyst regeneration zone 8 residual catalyst is separated from "red-oil" and various other reaction products. If desired, these other reaction products may be treated to recover for reuse a substantial part of their fluorine and antimony.

The hydrocarbon product is taken from settler 5 through line 9 into column 10. Here the isobutane which is unreacted is distilled overhead and returned through line 11 to the reactor. The debutanized gasoline at the bottom of column 10 is removed through line 12 and sent to storage.

Comparison of Example I, heptanes isomerized without isobutane using an antimony pentafluoride-fluorosulfonic acid mixture, and Example II, heptanes treated by the instant invention, shows that when isobutane is added (1) less acid soluble oil is formed (a measure of catalyst degradation), (2) about twice as much C_5 and C_6 products are produced, and (3) more of the higher octane isomers in the C_5 , C_6 and C_7 fractions are produced.

While the invention is described in connection with the specific Examples below, it is to be understood that these are for illustrative purposes only. Many alternatives, modifications and variations will be apparent to those skilled in the art in the light of the below Examples and such alternatives, modifications and variations will fall within the scope and spirit of the appended claims.

3
GENERAL PROCEDURE

For the runs made in Examples I and II below a mixture of 8 milliliters of antimony pentafluoride, 25 milliliters of fluorosulfonic acid and 225 milliliters of heptane was stirred at -10° C . Samples of the hydrocarbon product were withdrawn at intervals for analysis and analyzed using vapor phase chromatography.

EXAMPLE I

Feed composition, (weight percent):		10
Isobutane	0	
Heptanes	100	
Contact time, (hours)	7	17
Product composition (weight percent):		
Propane	1.7	3.4
Butanes	2.8	33.7
Pentanes	0.0	17.4
Hexanes	0.1	21.4
Heptanes	95.4	9.1
Acid-soluble oil	1.0	15.0
Pentane isomer distribution, (weight percent):		
Isopentane	91.1	
n-Pentane	8.9	
Hexane isomer distribution (weight percent):		20
Dimethylbutanes	68.6	
Other	31.4	
Heptane isomer distribution (weight percent):		
Dimethylpentanes	55.2	
Triptane	13.2	
Other	31.6	

EXAMPLE II

Feed composition (weight percent)		
Isobutane	50.7	
Heptanes	43.9	
Contact time (hours)	48	
Product composition (weight percent)		
Propane	1.8	
Butanes	43.9	30
Pentanes	19.8	
Hexanes	22.5	
Heptanes	12.1	
Acid-soluble oil	1.0	
Pentane isomer distribution (weight percent)		40
Isopentane	89.7	
n-Pentane	10.3	
Hexane isomer distribution (weight percent)		
Dimethylbutanes	77.1	
Other	22.9	45
Heptane isomer distribution (weight percent)		
Dimethylpentanes	76.8	
Triptane	5.7	
Other	17.5	

4

What is claimed is:

1. A process for upgrading the octane rating of a hydrocarbon feed which is a low octane heptane or a low octane mixture which is substantially composed of heptanes comprising:
  - (a) contacting said low octane heptane or said low octane mixture which is substantially composed of heptanes with isobutane in the presence of a fluorosulfonic acid-antimony pentafluoride catalyst at a temperature between about -20° F . and about 70° F ., and
  - (b) separating a mixture of higher octane hydrocarbons from the combination of step (a).
2. The process of Claim 1 wherein step (a) is carried out between about 0° F . and about 40° F .
3. A continuous process for upgrading the octane rating of a hydrocarbon feed which is a low octane heptane or a low octane mixture which is substantially composed of heptanes comprising:
  - (a) contacting said low octane heptane or said low octane mixture which is substantially composed of heptanes with isobutane in the presence of a fluorosulfonic acid-antimony pentafluoride catalyst at a temperature between about -20° F . and about 70° F ., and
  - (b) separating a mixture of higher octane hydrocarbons from the combination of step (a), and
  - (c) recycling the fluorosulfonic acid-antimony pentafluoride catalyst to step (a), and
  - (d) separating unreacted isobutane from said mixture of higher octane hydrocarbons and recycling said isobutane to step (a).
4. The process of Claim 3 wherein step (a) is carried out between about 10° F . and about 30° F . and at a space velocity of between about 0.05 volumes of said feed per volume of said catalyst to about 0.2 volumes of said feed per volume of said catalyst.
